J. WATSON,
STOVEPIPE JOINT,
APPLICATION FILED FEB. 20, 1920.

1,376,364.

Patented Apr. 26, 1921.

Fig. 1.

UNITED STATES PATENT OFFICE.

JAMES WATSON, OF MARINETTE, WISCONSIN.

STOVEPIPE-JOINT.

1,376,364.

Specification of Letters Patent. Patented Apr. 26, 1921.

Application filed February 20, 1920. Serial No. 360,266.

To all whom it may concern:

Be it known that I, JAMES WATSON, a citizen of the United States, residing at Marinette, in the county of Marinette and State 5 of Wisconsin, have invented a new and useful Stovepipe-Joint, of which the following is a specification.

It is the object of this invention to provide a novel form of foldable joint, adapted 10 to be used in a folding stove pipe, or upon a structure of any other kind, calling for a joint of the sort hereinafter described.

The invention aims to provide a joint which will be braced and reinforced when 15 two members are disposed at right angles to each other.

Another object of the invention is to provide a foldable joint of novel form wherein a hinge rod or pintle may be dispensed with. 20 It is within the province of the disclosure to improve generally and to enhance the utility of devices of that type to which the invention appertains.

With the above and other objects in view 25 which will appear as the description proceeds, the invention resides in the combination and arrangement of parts and in the details of construction hereinafter described and claimed, it being understood that, within 30 in the scope of what is claimed, changes in the precise embodiment of the invention shown can be made without departing from the spirit of the invention.

In the accompanying drawings:—

35 Figure 1 discloses in elevation, a flue or stove pipe embodying the invention, parts being broken away; Fig. 2 is a section taken on the line 2—2 of Fig. 1; Fig. 3 is a sectional view taken on the line 2—2 of Fig. 1, 40 but showing the parts as they will appear when folded together and when extending in the same direction; Fig. 4 is a section taken on the line 2—2 of Fig. 1 but showing the parts as they will appear when they 45 have been opened out, to extend in opposite directions; Fig. 5 is a perspective view showing one member of the joint; Fig. 6 is a perspective view showing the other member of the joint; Fig. 7 is a fragmental elevation showing a slight modification in the 50 invention; and Figs. 8 and 9 are diagrams, showing, respectively, the flue folded flat and opened up for use.

55 Referring particularly to Figs. 3, 2, 4, 5, and 6 of the drawings, the numeral 1 de-

notes a first member having a first trough-shaped bead 2, the numeral 3 denoting a second member having a second trough-shaped bead 4 received within the first bead 2. The beads 2 and 4 are resilient, and this 60 observation applies peculiarly to the bead 2. Let it be supposed that the members 3 and 1 are folded together, as shown in Fig. 3. Then, owing to the resiliency of the beads 2 and 4, when the members 1 and 3 65 are disposed substantially at right angles to each other, as shown in Fig. 2, the outer edge 5 of the first bead 2 engages the second member 3, the bead 2 being distorted out of its normal cylindrical form, to permit the 70 inner portion 6 of the first bead 2 to bind resiliently against the second bead 4. The construction is such that the members 1 and 3 are clamped or held firmly but yieldingly in rectangular relation to each other, as 75 shown in Fig. 2. The resiliency of the beads 2 and 4 permits the members 1 and 3 to be disposed in oppositely extended relation, as depicted in Fig. 4, the outer edge 7 of the 80 bead 4 being received within the bead 2, and the outer edge 5 of the bead 2 being received within the bead 4.

The beads 2 and 4 are of circular cross section, the bead 4 being telescoped within the bead 2. In order to prevent relative 85 longitudinal movement between the beads 2 and 4, openings 8 are fashioned in the members 1 and 3, relatively near to the respective beads, the said members having slots 9 communicating with the openings, the 90 slots permitting a ring 10 to be placed in the openings 8, the ring surrounding the beads 2 and 4. The ring 10 may be alluded to as an annular securing device preventing relative longitudinal movement between the 95 beads 2 and 4, and after this ring or securing device has been mounted in the openings 8, the slots 9 may be closed by spot welding or otherwise.

The device hereinbefore described may be 100 embodied in a collapsible flue, as shown in Fig. 1, such a flue being adapted for use on camping stoves and for other purposes, although the joint, it is to be understood, is of general application. If the structure 105 is embodied in a flue, then the members 1 and 3 may be provided, each, at one end, with an inset tongue 11, the construction being such that the upper end of one section of a flue may be telescoped within the lower 110

end of a superposed section of the flue, an operation which will be understood readily when Fig. 1 is noted.

In the modification shown in Fig. 7, parts 5 hereinbefore described have been designated by numerals previously used, with the suffix "a". In this form of the invention, the slots 9 are omitted, the ring 10 preferably being fashioned from a length of wire having its 10 ends hooked together, or otherwise engaged, as indicated at 14.

In either form of the invention, when the flue is set up, the ends of the beads abut, as shown at 12^a.

15 The flue may be folded flat, as shown in Fig. 8, Fig. 9 showing the flue opened into rectangular form for use.

Having thus described the invention, what is claimed is:—

20 1. A joint comprising a first member having a first trough-shaped bead; and a second member having a second trough-shaped bead received within the first bead, one of the beads being resilient whereby when the 25 members are disposed substantially at right angles to each other and when the outer edge of the first bead engages the second member, one of the beads will be distorted to permit the inner portion of the first bead 30 to bind resiliently against the second bead, the resiliency of the resilient bead permitting the first and second members to be disposed in oppositely extended relation, with the outer edge of each bead located within 35 the contour of the other bead.

2. A joint comprising a first member having a first trough-shaped bead; a second

member having a second trough-shaped bead received within the first bead, one of the beads being resilient whereby when the 40 members are disposed substantially at right angles to each other and when the outer edge of the first bead engages the second member, one of the beads will be distorted to permit the inner portion of the first bead 45 to bind resiliently against the second bead, the resiliency of the resilient bead permitting the first and second members to be disposed in oppositely extended relation, with the outer edge of each bead located within 50 the contour of the other bead, the first and second members being provided with openings; and an annular securing device engaged in the openings and surrounding the beads, the securing device constituting 55 means for limiting relative longitudinal movement between the beads.

3. A joint comprising first and second members provided with trough-shaped beads, the bead of one member being hingedly received within the bead of the other member, the said members having openings; and an annular securing device surrounding the beads and received in the openings, the securing device constituting means for limiting relative longitudinal movement between the beads.

In testimony that I claim the foregoing as my own, I have hereto affixed my signature in the presence of two witnesses.

JAMES WATSON.
